UNITED STATES PATENT OFFICE.

HATTIE JANE PAGE, OF GRAND RAPIDS, MICHIGAN.

WAIST-GARMENT.

1,006,590.

Specification of Letters Patent. Patented Oct. 24, 1911.

Application filed February 27, 1911. Serial No. 611,308.

To all whom it may concern:

Be it known that I, HATTIE JANE PAGE, a citizen of the United States, residing at Grand Rapids, in the county of Kent and State of Michigan, have invented certain new and useful Improvements in Waist-Garments, of which the following is a specification.

My invention relates to improvements in men's, women's, and children's garments, and its objects are: first, to provide garments that may be easily put on over the head and when on may be readily drawn to position to form a perfect fit upon the waist and around the neck without the use of buttons, hooks or other attached fastening device, and, second, to provide a means whereby the garment may be made to fit snugly around the waist line without danger of rendering it uncomfortable for the wearer. I attain these objects by the construction illustrated in the accompanying drawing, in which—

Figure 1 is a blank from which the back portion of the body and the front of the yoke is made. Fig. 2 is the same showing the blank for making the front portion of the body and a reinforcement for the back of the garment. Fig. 3 is a front elevation of the garment with the sleeves cut off short. Fig. 4 is a back elevation of the garment with the back cut away to show the construction of the inside of the front of the garment, and, Fig. 5 is a top view of the garment illustrating how it is to be drawn open at the neck to pass easily over the head of the wearer.

Similar letters refer to similar parts throughout the several views.

When manufacturing this garment from material that must be sewed I cut the blanks out substantially as shown in Figs. 1 and 2. I then turn the part A down over the part B, and the part A' down over the part B' and stitch each at the shoulders upon the lines c' d. I then reverse the two parts thus formed and slide the upper end of A' B' between the parts A B and stitch the parts B B' together along the lines c e to form the body. The yoke A is then stitched to the portion B' upon the lines c c'' to form an ornamental yoke upon the front of the waist, and the part A' is stitched to the inside of the portion B upon the lines c c'' to reinforce the back of the garment. When the two blanks have been sewed together upon the lines c c'' and c e, the sleeves C

are placed into the arm scyes and sewed to place on the lines c c', but the two portions are not sewed together on the shoulders from c' to d, which leaves the fabric free to be moved apart along this line. The garment is now practically completed so far as the neck and waist portions are concerned, and the opening a in the yoke portion A is situated down from the neck line b', over the front portion B' of the body of the garment, the edges of the fabric along the outline of this opening being provided with a narrow hem, or other ornamental finish, but is not sewed or otherwise secured to the front B, thus leaving the front beneath the yoke and the yoke over the front between the lines c c'' and over the shoulders free to be moved, folded or handled at pleasure, each independent of the other, and the opening a', from the shoulder line back and down is under the back portion B of the body of the garment, but, like the front yoke, the edges of the material each side of this opening is wholly free from attachment to the back B. By this line of connecting the two portions of the garment between the arm scyes, seams at c c' and the yoke seams c c'' are wholly detached so that the wearer may take hold of the collar at b and b' and draw them apart as indicated by the dotted lines in Fig. 5, to the positions shown at b'', which will tend to draw the arm scye seams to the positions indicated at c''' and will provide a large opening at the neck, facilitated by the openings a a', applied as hereinbefore stated, through which the head may be readily passed, when by drawing outward upon the sleeves C C the neck will be closed to its normal position and the garment will retain its form, position and perfect fit upon the wearer without the necessity of buttoning, hooking, or otherwise securing the parts together at the shoulders, neck or other part of the garment.

This garment may be worn without a collar, or any desired form of collar may be worn upon or with it, in any manner convenient or pleasing to the wearer.

That this garment may be made to properly retain its form and fit upon the wearer it is necessary to provide some means whereby the lower end of it will properly retain its position at the waist, and for this purpose I place a narrow strip of elastic fabric, as D, around the bottom of the garment, that is

made small enough to bind closely, but freely around the waist of the wearer.

When making these jackets upon knitting machines, it is readily understood that it will be made seamless except at the arm scye.

In the foregoing description I have placed the visible opening *a* at the front of the garment, but it will be readily understood that this is simply a matter of the manner of uniting the two blanks shown in Figs. 1 and 2. If they are placed as hereinbefore described the visible opening, *a*, must be in front and the invisible opening *a'* in the back of the garment, but if the construction is reversed, that is, if the blank shown in Fig. 1 is placed inside of, or between the two parts of the blank shown in Fig. 2 the visible opening, *a'* would be in the back of the garment and the opening *a* would become invisible because it would be under the part *B'*. In other words, a garment made so that it could be reversed would show the visible opening in front if worn one side out, and in the back if worn the other side out, and the garment may be readily made to be worn either side out as the wearer may desire or convenience may dictate.

It will be readily understood that the yoke and neck construction hereinbefore described and shown in the drawings may be used upon any kind of waist garment, as jackets, sweaters, negligée shirts, night dresses, kimonas, dressing sacks or any waist garment made from cloth or other available fabric.

When cutting out this garment I find it very advantageous to cut out a gore and stitch the yoke and body portions together on the lines *c' d* to give the shoulders good form. The peculiar V shaped form of the yokes, and the V shaped openings *a*, *a'*, from the neck openings *b*, *b'* well down

into the yokes, but not disconnecting the yokes at the points *c''*, and the sewing of the yokes to the body on the lines *c'', c, c'*, ⁴⁵ are quite necessary elements to properly draw the yokes to place to form a smooth closely fitting and well proportioned garment around the neck and shoulders, that will not gape, wrinkle or become disordered by the natural movements of the body of the person wearing the garment. This construction, at the same time, places but two thicknesses of fabric over the shoulders and gives to the waist the appearance of a tasty, ⁵⁵ close fitting vest that will hold its position on the person without the use of hooks, buttons or other form of fastening.

What I claim as new, and desire to secure by Letters Patent of the United States, is: ⁶⁰

In a waist garment, a front body portion having a yoke cut integral therewith and a curved neck opening in the body continuing to a long V shaped opening in the yoke portion, a back body portion having a yoke portion cut integral therewith and a long V shaped opening therein, the body portions sewed together at the meeting edges and each yoke sewed at the outer edges to the opposite body portion, a gore cut from each shoulder between each body portion and its integral yoke portion, and the parts sewed together to give correct shoulder form, the garment provided with arm scyes, and so arranged that a large opening may be readily formed at the neck, and as readily contracted to form a close fitting neck opening, ⁷⁰ substantially as shown and described.

Signed at Grand Rapids Michigan February 25, 1911.

HATTIE JANE PAGE.
